Des. 181,550
Patented Nov. 26, 1957

181,550

MONEY-CLIP OR SIMILAR ARTICLE

Sidney Rubeck, New York, N. Y.

Application May 14, 1957, Serial No. 46,153

Term of patent 7 years

(Cl. D17—3)

Fig. 1 is a front perspective view of a money-clip or similar article showing my new design.

Fig. 2 is a rear perspective view.

Fig. 3 is a plan view of the money-clip in open position.

I claim:

The ornamental design for a money-clip or similar article, substantially as shown.
